[57] CLAIM

The ornamental design for a saw table, substantially as shown and described.

DESCRIPTION

FIG. 1 is a perspective view of a saw table showing our new design, the multipurpose woodworking table being shown in broken lines for illustrative purposes only; FIG. 2 is a perspective view thereof taken from a different angle;

FIG. 3 is an enlarged front elevational view thereof;

FIG. 4 is an enlarged top plan view taken in the direction of the arrows on line 4—4 of FIG. 3;

FIG. 5 is an enlarged sectional view taken in the direction of the arrows on line 5—5 of FIG. 3;

FIG. 6 is an enlarged sectional view taken in the direction of the arrows on line 6—6 of FIG. 3;

FIG. 7 is an enlarged bottom plan view taken in the direction of the arrows on line 7—7 of FIG. 3;

FIG. 8 is an enlarged rear elevational view thereof;

FIG. 9 is an enlarged elevational view taken in the direction of the arrows on line 9—9 of FIG. 8;

FIG. 10 is an enlarged side elevational view taken in the direction of the arrows on line 10—10 of FIG. 8.
